(57) **CLAIM**

The ornamental design for a beach blanket as shown and described.

DESCRIPTION

FIG. 1 is a perspective view of a beach blanket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the beach blanket where the beach blanket is in a folded state;

FIG. 10 is a perspective view thereof where a buckle is unbuckled;

FIG. 11 is an enlarged view of portion 11 shown in FIG. 1;

FIG. 12 is an enlarged view of portion 12 shown in FIG. 1; and,

FIG. 13 is an enlarged view of portion 13 shown in FIG. 2. The dot-dash broken lines in FIGS. 1, 2, and 11-13 depict boundary lines of the enlargement views and form no part of the claimed design.

1 Claim, 13 Drawing Sheets
